UNITED STATES PATENT OFFICE.

LEHMAN WEIL, OF NEW YORK, N. Y.

FLYING MACHINE.

Application filed April 15, 1925. Serial No. 23,307.

To all whom it may concern:

Be it known that I, LEHMAN WEIL, a citizen of the United States, and a resident of the city of New York, borough of Manhattan, in the county and State of New York, have invented a new and Improved Flying Machine, of which the following is a full, clear, and exact description.

This invention relates to flying machines, and of the type adapted particularly to be operated by man power, but may, if desired, be driven in the usual manner by an engine.

An object of the invention is the provision of a flying machine having pairs of oscillating wings at its front and rear ends adapted to be operated by foot pedals for driving the flying machine forwardly with sufficient speed that the device will be elevated in the usual manner.

Another object of the invention is the provision of a flying machine having pairs of oscillating propellers at its forward and rear ends, the propellers consisting of a plurality of blades in vertical alignment and automatically operated to open position during the return of the oscillating blades but closed during the propelling movement.

A further object of the invention is the provision of a flying machine having forward and rear vertically disposed propellers consisting of a plurality of vertically aligned blades having plane surfaces and co-operating concavo-convex surfaces which are normally forced against the air in one direction for propelling the flying machine, but are positively placed in a horizontal position upon the return or inoperative strokes of the propellers.

A still further object of the invention is the provision of an operating mechanism for actuating vertically disposed oscillating propellers which include a plurality of oscillating blades with mechanism for controlling the actuation of the oscillating blades.

With the above recited and other objects in view, the invention resides in the novel construction set forth in the following specification, particularly pointed out in the appended claims and illustrated in the accom-

panying drawings, it being understood that the right is reserved to embodiments other than those actually illustrated herein, to the full extent indicated by the general meaning of the terms in which the claims are expressed.

In the drawings—

Figure 1 is a view in perspective of a flying machine constructed according to the principles of my invention, with the omission of the operating mechanism;

Figure 2 is a vertical longitudinal section of the flying machine; and

Figure 3 is a plan view of the same.

Referring more particularly to the drawings, a frame is more or less diagrammatically shown of the stream-line type, to which is secured in spaced relation vertically disposed struts 1 and 2 adapted to support in the usual manner a pair of planes 3 in spaced relation above the body 4 of the frame. The frame is adapted to be covered in the usual manner. Pivotedly mounted at the rear end, as shown at 5, is an elevator 6 having the usual cables 7 and 8 connected to opposite sides of the elevator, as shown at 9, and directed forwardly and connected to an operating stick 10 which is pivotedly mounted at a point adjacent the seat 11 of the operator, the seat being supported upon the floor 12 of the body 4 of the flying machine. The cables 7 and 8 are entrained over pulleys in order to maintain the proper alignment and support the cables in a well known manner.

The bars 13 connected with the body 4 depend below the floor 12 and are provided with bearings in which is rotatably mounted a shaft 14. To said shaft are secured wheels 15 adapted to normally engage the ground. Bars 16 of the frame or body are extended below the floor 12 and carry an axle 17 upon which are loosely mounted wheels 18 disposed forwardly of the wheels 15. Adjacent the rear end are provided depending bars 19 carrying an axle 20 for supporting wheels 21 which engage the ground at the rear when the body tilts rearwardly.

A rudder 22 is pivotally mounted at 23 upon the rear end or tail 24 of the flying

100

2
machine and is adapted to be oscillated laterally by means of cables 25 connected with the rudder and directed forwardly and secured to a vertical shaft 26 located adjacent the seat 11 and which has an operating wheel 27.

A pair of propellers generally designated by the numerals 29 and 30 are pivotally mounted at 31 and have a rearward extension 32. Each of the propellers includes a rigid frame 33 and a plurality of vertically disposed blades 34 hingedly mounted at their upper ends to the vertical bars 35 and 36 of the frame. Each of the blades has a plane surface 37 and a concavo-convex surface 38 located forwardly of the plane surface and projecting beyond the end bar 35 of the frame 33. The member 38 in each blade of the propeller is curved in such a manner that it will form a pocket to receive the air when the propeller is oscillated rearwardly or towards the body of the aero-plane.

A link 39 is connected to the extension 32 of the propeller 29, and this link is connected to a lever 40 rigidly mounted on a shaft 41 which is actuated by a lever 42, a link 43 and a lever 44 rigid with a shaft 45. The shaft 45 is mounted in bearings on a standard 46, and a sprocket 47 rigid with shaft 45 is driven by a chain 48, and sprocket 49 secured to a shaft 50. This shaft is provided with a pair of cranks 51 adapted to be actuated by right and left treadles 52 and 53 which are pivotally mounted at their outer ends on the shaft 45. These treadles are actuated by the operator of the car and are disposed below and adjacent the seat 11. The shaft 50 is carried by brackets 54 mounted on the frame of the flying machine.

A second link 55 is connected to the extension 32 of the propeller 30 and is also connected to a lever similar to the lever 40 which is rigid with the shaft 41 so that when the treadles 52 and 53 are operated alternately, both propellers will be oscillated towards and away from the axis of the body.

50 The frame 33 is provided with a depending bar 56 carrying a wheel 57 which is adapted to engage the ground when the machine alights and to prevent injury to the propellers at this time, for otherwise the propellers might be abruptly forced into the ground as the machine is tilted and engages the surface of the landing place.

A pair of rear propellers are provided, as shown, having a hinged mounting at 58 on the corner posts of the frame, and a bar 59 rigid with the frame 60 of the rear propellers carries the hinged mounting of the rear propellers. Each of these rear propellers are provided with a plurality of vertically aligned blades having plane sur-

faces 61 and concavo-convex surfaces 62 projecting rearwardly from the plane surfaces 61 and, as shown more particularly in Figures 3 and 4, the propellers are adapted to be moved simultaneously and with the pair 70 of the planes at each end and on the same side of the axis of the frame moving towards or away from each other. The rear propellers are operated by a mechanism similar 75 in all respects to the operating mechanism for the front propellers and include links 63, levers 64 and 65, a shaft 66, a link 67, a lever 68 connecting the link 67 to a shaft 69, a chain 70 and sprockets 71 and 72, the sprocket 72 being rigid with the shaft 50. 80

The blades 34 of the front propellers and the blades of the rear propellers are positively actuated on their respective frames so that when the propellers are moved rearwardly in each case, the blades will be in 85 closed position to beat against the air, while when moving forwardly they are positively positioned in a horizontal plane in order to eliminate the action of the air on the blades so that there will be no interference and the 90 flying machine may be readily driven forwardly.

As shown more particularly in Figure 2, the lower end of each of the blades is pivotally connected to a rod 73 which, by means 95 of a link 74, is connected to a crank shaft 75. This crank shaft is operated through a sprocket 76, a chain 77 and a sprocket 78 mounted on a shaft 79. This shaft is driven through a sprocket 80 on a shaft 79, a chain 81 and a sprocket 82 secured to a shaft 83. A toothed wheel 84 is rigid with the shaft 83 and is adapted to be engaged by a pair 100 of pins 85 located at diametrically opposite points on a wheel 86. This wheel is driven by a shaft 87, which in turn is driven by a chain 88 and a sprocket 89 on a shaft 45. 105

An instrument board 90 is located adjacent the seat 11.

A sprocket 93 is rigidly connected with the shaft 50 and drives a chain 94, which in turn drives a sprocket 95. The last mentioned sprocket drives the shaft 14 and therefore causes the wheels 15 to be re- 110 volved, which aids in propelling the flying machine when the same is on the ground and which is adapted to operate as a fly-wheel when the flying machine is in flight. 115

The operation of my device is as follows:

After the operator has taken his position 120 on the seat 11 and operated the stick 10 to raise the elevator 6, the treadles 52 and 53 are then actuated, setting in motion the wheels 15 the front oscillating propellers 29 and 30 and rear propellers 60^a. While the propellers 29 and 30 are moved rearwardly against the air, the propellers 60^a are moved forwardly with the air and the blades of the rear propellers are placed in a horizontal position by means of the mechanism 125 130

just described, so that no friction will be had at any time when the propellers are moving with the direction of the flying machine. The forward propellers beating 5 against the air will force the flying machine forwardly and on their return or inoperative stroke their blades will be moved to a horizontal or inoperative position while the blades of the rear propellers will be placed 10 in a vertical or operative position and, beating against the air, will also force the flying machine forwardly. It will be noted that the continuous operation of the propellers will force the flying machine forwardly at such speed that the air engaging 15 beneath the plane 3 will cause the machine to rise from the ground.

It will also be noted that the concavo-convex portions 38 of the front propellers 20 and the similar pockets 62 of the rear propellers have their greatest depth as shown at 91 adjacent the outer end of the plane surfaces of the propellers so that the pocketing of the air will have its greatest effect at 25 this point and, furthermore, when the blades are placed in a horizontal position, the gradual lessening of the depth of the pocket will tend to aid the ready discharge of the air from said pockets.

30 The front and rear set of vertical propellers swing in opposite directions, first, for the purpose of balancing each other, and, second, to produce a steady, continuous forward movement. If these propellers move in the same direction at the same time, the tendency for the machine would be to tilt or fall, and by reason of this particular action this tendency is eliminated.

It is also to be understood that not only 40 the biplanes shown in the drawings but any other kind of supporting surface mounted on the body of the flying machine can be used, such other surfaces being monoplanes, multiplanes, planes at tandem, etc. The use 45 of the automatic device for the opening and closing of the oscillating blades of the vertical propellers at the proper moment, that is, the moment the vertical propellers start to swing forwardly or rearwardly, is absolutely necessary for the safe and efficient 50 operation of the flying machine for the following reasons:

The arrangement and hinging of the oscillating blades to the frame of the vertical propeller allow, owing to the pressure exerted by the blades against the air, the blades to open and to close automatically 55 without the use of the automatic device provided the weather is perfect, calmness of the air prevailing; (1) but even then as soon as the flying machine is in motion, and more so in rapid flight, the pressure of the air against the front of the rearwardly swinging vertical propellers will, without the use 60 of the automatic device, force the blades

open, thus rendering the vertical propellers impotent for the performance of their proper functions and make the operation of the flying machine extremely dangerous and in fact impossible as the flying machine 70 becomes unmanageable.

(2) The pressure of strong air currents blowing in the opposite direction to the course of the flying machine will also force 75 open, without the use of the automatic device, the blades of the rearwardly swinging vertical propellers.

(3) Air currents moving at right angle 80 or any other angle to the direction of the course of the flying machine will keep, without the use of the automatic device, the blades of the forwardly swinging vertical propellers open and prevent them from closing at the proper moment when the propellers start to swing rearwardly.

Having thus described my invention, I claim:

1. In a flying machine, a body, pairs of propellers hingedly mounted at the forward and rear ends of said body, and means 90 for oscillating a pair of the propellers at each end towards or away from each other, each of the propellers comprising a plurality of pivotally mounted blades and means 95 for positively oscillating the blades.

2. In a flying machine, a body, pairs of propellers hingedly mounted at the forward and rear ends of said body, means for oscillating a pair of the propellers at each end 100 towards or away from each other, each of the propellers comprising a plurality of pivotally mounted blades disposed in a vertical plane, and means for moving the blades to an angle of 90°.

3. In a flying machine, a body, pairs of propellers hingedly mounted at the forward and rear ends of said body, means for oscillating a pair of the propellers at each end towards or away from each other, each 110 of the propellers comprising a plurality of pivotally mounted blades disposed in a vertical plane, and means for moving the blades from a vertical to a horizontal position and for returning the blades to their vertical positions.

4. In a flying machine, a body, pairs of propellers hingedly mounted at the forward and rear ends of said body, and means for oscillating a pair of the propellers at each end towards or away from each other, each of the propellers comprising a plurality of pivotally mounted blades, the ends of the blades being provided with pockets.

5. In a flying machine, a body, pairs of propellers hingedly mounted at the forward and rear ends of said body, and means for oscillating a pair of the propellers at each end towards or away from each other, each of the propellers comprising a plurality of pivotally mounted blades, the 125 ends of the blades being provided with pockets.

ends of the blades being provided with a pocket which decreases in depth from its inner end to its outer.

6. In a flying machine, a body, pairs of propellers hingedly mounted at the forward and rear ends of said body, means for oscillating a pair of the propellers at each end towards or away from each other, each of the propellers comprising a plurality of pivotally mounted blades, means for oscillating the blades towards or away from the propellers, and a common means for cooperatively oscillating the propellers and simultaneously operating the blades.

7. In a flying machine, a body, pairs of propellers hingedly mounted at the forward and rear ends of said body, each of said propellers comprising a frame pivotally mounted on the body and blades disposed in vertical alignment and hingedly connected at spaced points with the frame, and means for swinging the blades towards the frame when the propellers are operatively moved and for swinging the blades away from the frame when the propellers are being moved to an inoperative position.

8. In a flying machine, a body, pairs of propellers hingedly mounted at the forward and rear ends of said body, each of said propellers comprising a frame pivotally mounted on the body and blades disposed in vertical alignment and hingedly connected at spaced points with the frame, and means for swinging the blades towards the frame when the propellers are operatively moved and for swinging the blades away from the frame when the propellers are being moved to an inoperative position, the outer ends of the propellers being provided with pockets and forming part of the blades.

9. In a flying machine, a body, pairs of propellers hingedly mounted at the forward and rear ends of said body, each of said propellers comprising a frame pivotally mounted on the body and blades disposed in vertical alignment and hingedly connected at spaced points with the frame, and means for swinging the blades towards the frame when the propellers are operatively moved and for swinging the blades away from the frame when the propellers are being moved to an inoperative position, the similarly positioned propellers at the front and rear of the machine moving in opposite directions, the operating means for swinging the blades being adapted to cause swinging in the opposite direction, causing the blades of the rear propeller to swing in an opposite direction from the blades of the front propellers.

10. In a flying machine, a body provided with rigid struts, parallel planes spaced from each other and tilted upwardly from the horizontal at their forward ends, oscil-

lating propellers connected in pairs at the opposite ends of the body, means for oscillating the propellers, a shaft supported below the body member, and wheels rigid with the shaft for supporting the flying machine on the ground, and means connecting the operating means for oscillating the propellers for causing rotation of the shaft and propulsion of the flying machine when on the ground.

11. In a flying machine, a body provided with rigid struts, parallel planes spaced from each other and tilted upwardly from the horizontal at their forward ends, oscillating propellers connected in pairs at the opposite ends of the body, means for oscillating the propellers, a shaft supported below the body member, and wheels rigid with the shaft for supporting the flying machine on the ground, means connecting the operating means for oscillating the propellers for causing rotation of the shaft and propulsion of the flying machine when on the ground, an elevator pivoted at the rear end of the body member, and a rudder pivoted at the rear end of the body and below the elevator.

12. In a flying machine, a body, pairs of propellers hingedly mounted at the forward and rear ends of said body, means for oscillating pairs of the propellers towards or away from each other, said means comprising a pair of treadles, means for connecting the treadles to a crank shaft, a pair of levers connected together at their free ends by a link, a shaft rigid with each lever, means operatively connecting the shafts with the crank shaft, and means connecting one of the pairs of shafts with an oscillating propeller.

13. In a flying machine, a body, pairs of propellers hingedly mounted at the forward and rear ends of said body, each of said propellers comprising a plurality of pivotally mounted blades disposed in vertical alignment, a rod pivotally connected to the lower end of each blade, a crank shaft, a link connecting the first mentioned rod with the crank shaft, a wheel having a pair of pins at diametrically opposite points, a toothed wheel adapted to be engaged by the pins for periodically operating the toothed wheel, and means operatively connecting the toothed wheel with the crank shaft whereby the blades are periodically oscillated.

14. In a flying machine, a body, pairs of propellers hingedly mounted at the forward and rear ends of said body, each of said propellers comprising a plurality of pivotally mounted blades disposed in vertical alignment, a rod pivotally connected to the lower end of each blade, a crank shaft, a link connecting the first mentioned rod with the crank shaft, a wheel having a pair of

- pins at diametrically opposite points, a toothed wheel adapted to be engaged by the pins for periodically operating the toothed wheel, means operatively connecting the toothed wheel with the crank shaft whereby the blades are periodically oscillated, and means for oscillating the propellers, said last mentioned means being so timed with the operating means for the blades that as a propeller is moved forwardly the blades are moved to an open position or when the propeller is moved rearwardly on its inoperative stroke the blades are closed.
- 15 15. In a flying machine, a body, pairs of propellers hingedly mounted at the opposite ends of said body, means for oscillating pairs of propellers at the ends towards or away from each other, each of said propellers consisting of a frame hingedly mounted on the body and blades disposed in vertical alignment and having hinged connections at their tops with the frame, wheels for normally supporting the body of the flying machine, and a wheel carried by the frame at the forward ends of the aeroplane for engaging the ground to prevent injury to the forward propellers.

LEHMAN WEIL.
